UNITED STATES PATENT OFFICE.

JOHN BOSSART, OF LOS ANGELES, CALIFORNIA.

ROCK CRUSHER.

Application filed February 14, 1928. Serial No. 254,302.

This invention relates to a rock crusher having a crusher head adapted for rapid gyratory movement.

Among the objects of the invention are to increase the amount of production secured by a given expenditure of power, to provide improved means for keeping the dust out of the working parts, to provide an arrangement of working parts peculiarly adapted to withstand the vibration and strain of rapid movement during operation, with the minimum amount of friction and to simplify and improve upon the construction of rock crushers in other particulars, as will more fully hereinafter appear.

Referring to the accompanying drawings which illustrate a preferred embodiment of the invention,

Figure 1 is a vertical mid-section of the complete crusher.

Figure 2 is a top view of Figure 1 partly in section, the plane of section being indicated by the line 2—2 on Figure 1.

Figure 3 is a broken side elevation of a portion of Figure 1 looking at the right side of the latter view.

Referring in detail to the drawings, within an upright cylindrical casing 5 is mounted a gyratory conical crusher head 6, the upwardly directed apex 7 of which is surrounded by a stationary crusher head 8 which encloses a feed opening 9 and is surmounted by a hopper 10.

The lower portion of the conical stationary head 8 is surrounded by a radial flange 11 whereby it is secured to the top flange 12 of the casing 5. The fastening means employed for this purpose desirably consist of bolts 13 having nuts 14 on their upper ends which screw down upon washers 15, a strong compression spring 16 being interposed between each washer 15 and the upper surface of the flange 11. By screwing down the nut 14 the head 17 of the bolt is brought up against the under surface of the flange 12 under the desired pressure.

The movable crusher head 6 is secured to the upper end of an upstanding shaft 20, said head 6 having an attaching shank 21 provided with a bore preferably somewhat larger than the shaft 20 so that an annular space filled with the metallic bond 22 consisting of metal poured into place in a molten condition may be used to secure shaft 22 to shank 21. To the lower end of shaft 20 is secured a spheroidal head 23 which is operatively connected with

the driven wheel 24 in eccentric relation thereto by means of the wheel flange 25, semi-circular clamping member 26 and clamping bolts 27.

The movable crusher head 6 is provided with a downwardly directed skirt or flange 30 which is in outwardly spaced relation to the body portion of said head, thus providing room for an annular guide 31 between said body and flange, said space being also sufficient to allow considerable gyratory play of the head within said guide as shown in Figure 1. Said guide 31 is supported by the upper end of a tubular standard 32 having radial arms 33 whereby it is desirably made integral with the frame or casing 5. The mounting of the guide 31 upon said standard 32 is accomplished by means of providing said guide with a peripheral downwardly directed flange 35 which fits over the top of said standard 32. The upper end of the flange portion 31 is provided with an annular shoulder 36 upon which the skirt 30 of the movable crusher head rests at one side at all times.

The standard 32, having an external diameter considerably less than the internal diameter of the casing 5, an annular delivery space or passage 37 is provided down which the crushed rock passes and from the lower end of which it is delivered by the diametrically opposite delivery openings 38, said openings being located at right angles to the belt 39 which drives the wheel 24. An upwardly arched wall 40 forms the floor of the annular chamber 37.

Near the lower end of the casing 5 is provided a bearing 45 to support the wheel 24, said bearing being desirably supported by an arm 46 which may be cast as a part of casing 5. Said arm 46 is shown as terminating in a semicircular head or flange 47 which cooperates with the bearing cap 48 to form a bearing for the stub shaft 49 of the wheel or pulley 24, bolts 50 being used to clamp said bearing cap to said head 47.

The stationary crushing head 8 is not uniformly conical but has a lower crushing face 50 which is less inclined than the crushing face 51 which extends upwardly from said face 50 to form a continuation of the stationary crushing surface. Owing to this arrangement of the crushing faces the portion of the crushing face of the movable head 6 nearest the apex thereof is surrounded by a wider feed passage than is the portion of said head 6 which is opposite to the stationary

crushing surface 50. With this arrangement of crushing surfaces, a slow rotation of the wheel 24 would not result in an effective operation of the crusher because, viewing the parts as shown in Figure 1, undesirably coarse material would escape from the right side of the crushing elements while the proper crushing function was taking place at the left side. But by refraining from supplying any rock 10 to the feed hopper until the motor (not shown) has attained a speed sufficient to rotate the wheel 24 at about 400 revolutions per minute, the movable crusher head 6 is gyrated so rapidly that the rock passing between 15 the crushing surfaces cannot descend by gravity fast enough to escape being crushed by the time it reaches the lower portion 50 of the stationary crusher head.

In order to prevent dust and dirt from 20 entering the bearing for the spheroidal head 23, the lower end of shank 21 is provided with a circular downwardly inclined flange 55 and an apron 56 is secured to the lower edge of said flange and envelops the top of the bearing formed by members 25 and 26.

The parts 25 and 26 are provided with an externally grooved top 55 to receive a spring retaining ring 57^a to clamp the lower end of the apron 56 in place.

30 I claim:

1. In a crusher, a gyratory crusher head having an upwardly directed apex, the conical portion of said head being terminated by the top of a downwardly directed skirt, said 35 skirt being outwardly spaced with relation to the body portion of said head, a fixed circular guide inclosed by said skirt, the external diameter of said guide being substantially the same as the internal diameter of said skirt, a shaft for said head extending downwardly therefrom and means operatively engaging said shaft at a distance below said head to impart a gyratory movement thereto.

2. In a crusher, a gyratory crusher head, 45 said head being provided with a downwardly extending tubular shank having around its lower end a downwardly directed flange, a driving shaft within said shank and projecting there-beneath, a wheel provided with an eccentric bearing to which the lower end of said shaft is connected, a circular apron connected with said downwardly directed flange at its top and with said bearing at its lower edge to keep dust therefrom, and means for 50 guiding the gyratory movement of said head.

3. In a crusher, a gyratory head having a top surface adapted to receive and distribute material to be crushed, said head having at its lower side a downwardly directed skirt, 60 said skirt being outwardly spaced with relation to the body portion of said head, a fixed circular guide inclosed by said skirt, a portion of said skirt in all its operative positions overhanging the top of said guide and being centered thereby, there being a rolling contact between said guide and said skirt, an operating shaft for said head extending downwardly therefrom and means operatively engaging said shaft at a distance below said head to impart a gyratory movement thereto.

4. In a crusher, a gyratory crusher head having a top portion adapted to receive material to be crushed, said head being terminated below by the top of a downwardly directed peripheral flange, a stationary circular guide within said flange, said guide being constructed and arranged positively to prevent lateral shifting of said head from its center of gyration, means to gyrate said head, a stationary crusher head located above and adapted to cooperate with said gyratory head, a shaft for gyrating said head extending downwardly therefrom, and a driving wheel for gyrating said shaft operatively connected therewith in an eccentric manner.

In testimony whereof I affix my signature.
JOHN BOSSART.
